COAL STOVE

John C. Miles, Urbana, Ill., assignor to The University of Illinois Foundation, a nonprofit corporation of Illinois

Application June 2, 1947, Serial No. 751,906

2 Claims. (Cl. 126—73)

1

This invention relates to a coal stove and particularly to a coal stove having a by-pass leading from the fire box of the stove to an exit for the gases of combustion and a cooperating door arranged to communicate between the exterior of the stove and the interior of the fire box through the opening that is normally closed by the by-pass door. The invention also relates to means for opening and closing the doors together.

It has been proposed in the past to provide a by-pass door between the fire box and the passageway that is provided for the gases of combustion with this door being capable of being opened prior to the introduction of coal into the fire box. There is also provided a door between the exterior of the stove and the fire box so that fresh coal can be introduced to the fire box. The by-pass door permits venting of smoky gases in the fire box when the exterior door is opened for the introduction of coal or for other reasons so that these gases will not escape to the exterior of the stove. In the improved construction, which forms the subject matter of this invention, the by-pass door and the exterior door are aligned with each other so that coal may be introduced into the fire box through the openings normally closed by said doors. Means are provided for opening both doors. It is preferred that the doors be so arranged that the by-pass door may be opened to give complete communication between the fire box and the passageway for burnt gases before the exterior door gives complete communication with the exterior of the stove. This permits any gases in the fire box to be vented to the gas passageway before these gases have an opportunity to escape through the exterior door. Means are preferably provided connecting the doors so that both doors are opened and closed together.

It is preferred that the by-pass door be arranged at or near the top of the fire box with the exterior door being arranged adjacent the by-pass door. This permits the complete filling of the fire box with coal thereby leaving no empty space for the accumulation of combustion gases formed in the coking of the coal. This formation of gases in a pocket in the fire box is eliminated so as to avoid what is known as "puff back." This is caused by air entering the portion of the fire box occupied by these heated combustion gases and causing miniature explosions. These explosions result in smoke being forced out into the room.

The invention will be described as related to the embodiments shown in the accompanying drawings. Of the drawings: Fig. 1 is a fragmentary vertical section through a stove embodying the invention; Fig. 2 is a fragmentary elevation of the stove of Fig. 1 showing the exterior

2

door; and Fig. 3 is a section taken along line 3—3 of Fig. 1.

In the embodiment shown in Figs. 1, 2 and 3, the stove comprises an outer shell 10, a fire box 11, a grate 12 beneath the fire box, an inclined wall 13 defining one side of the fire box and having spaced openings 13a therein, a vertical wall 14 on the opposite side of the fire box and spaced from the outer shell 10 with this wall also having spaced openings 14a therein, a steeply inclined wall 15 at the top of the fire box formed of fire brick or the like, a combustion zone 16 above the fire box and communicating therewith through a relatively narrow throat 16a, and a stack 17 for the exhaust of the gases of combustion. The bottom of the stove is provided with an ash receptacle 18 beneath the grate 12 and this portion of the stove is provided with a door 19 through which the receptacle 18 may be removed. The space between the inclined wall 13 and the shell 10 of the stove is provided with a baffle 20 extending from the shell to a point adjacent the bottom of the wall 13. Air is admitted to the stove through a pair of openings 21 and 22 in the shell 10 on either side of the baffle 20. These openings are arranged so as to be opened and closed by a single damper 23 that is mounted on a threaded bolt 24 engaging a hole in the shell 10 adjacent the top end of the baffle 20. Air entering the top hole 21 flows through the openings 13a in the wall 13 into the fire box. This air serves as coking air for the coal in the fire box. Air entering the bottom hole 22 is directed downwardly by the baffle 20 to the region under the grate 12. Some of this air flows through the grate 12 and serves as coke-burning air. Another portion of the air flows up between the vertical wall 14 and the shell 10 of the stove through the openings 14a and through the throat 16a into the combustion zone 16. With this arrangement, the full supply of air to the stove is controlled by the single damper 23.

Near the top of the fire box 11 there is located a by-pass door 25 communicating between the top of the fire box and the passageway 26 for gases of combustion. As shown in Fig. 1, this passageway is the entire top of the stove. This top portion of the stove is lined with fire brick 27 or the like and is provided with an outwardly extending baffle 27a, also of fire brick, on the side of the stove opposite the location of the by-pass door 25. The gases of combustion leaving the combustion zone 16 are directed by the baffle 27a toward the other side of the stove and then back up through the stack 17 that is located immediately above the baffle 27a. When the by-pass door 25 is opened, any gases in the fire box 11 are vented to the passageway 26. The amount of gases in the fire box will be quite small, however, as the fire box

is ordinarily kept almost completely filled with coal.

Located adjacent the by-pass door 25 is an exterior door 28 communicating with the exterior of the stove. The by-pass door 25 is hinged mounted on the exterior door 28 by providing a pair of spaced brackets 25a formed integrally with the by-pass door 25 and extending toward the exterior door 28. These brackets have their outer ends attached by a hinge 29 to the exterior door 28. This hinge is substantially horizontal. Rigidly mounted on the hinge 29 is an operating arm 30 extending through the exterior door 28 and having its outer end 30a extending upwardly. This outer end is provided with a hand-engageable portion 30b of coiled wire.

The exterior door 28 is hinged mounted on the shell 10 of the stove by means of a vertical hinge 31 mounted on a door frame 32. When it is desired to introduce coal into the fire box 11, the operating arm 30 is turned so that its outer end 30a is pointed outwardly. This turns the by-pass door 25 up against the exterior door 28 and to the position shown in dotted lines in Fig. 1. Both the by-pass door 25 and the exterior door 28 may then be opened around the hinge 31 upon which the exterior door is mounted. Coal may then be introduced into the fire box through the openings normally closed by the doors 25 and 28. Means are preferably provided for releasably retaining the by-pass door 25 in a position against the exterior door 28. As shown, this means may comprise a spring-pressed ball 33 in the top of the exterior door 28. With this arrangement, the by-pass door may be released either by jarring the exterior door 28 against its frame or by turning the operating arm 30.

The top edge 25b of the by-pass door 25 is inclined so as to seat against an inclined surface on a frame member 34 located at the top of the fire box 11. The sides of the by-pass door 25 seat on raised portions 34a on the frame member 34 so that the sides of the by-pass door may be spaced inwardly and not scrape side flanges 34b that connect the exterior door frame 32 and the interior frame 34. The bottom edge of the by-pass door 25 seats against the bottom of the inner frame 34 as shown in Fig. 1.

With the arrangement just described, coal may be fed through the by-pass door 25 so that the fire box 11 may be substantially completely filled. The exterior door 28 need not have a close fit with its frame as any leakage around this door will go directly into the top passageway 26. The by-pass door 25 need not have a close fit with its frame as the draft pressure differential across this door is low due to the stack effect of the passageway 26. Any leakage around this door will therefore be low. Thus, ground joints or gaskets are not necessary with the doors 25 and 28. Any air leaking around the by-pass door 25 will still be contained within the stove. The by-pass door protects the exterior door 28 and prevents the formation of condensed tar or other material on the exterior door. Very little tar will form on the by-pass door 25 as this door is maintained quite warm. The location of the exterior door 28 provides adequate visibility and accessibility to the top portion of the stove above the fire box. The two doors also permit ready visibility and accessibility into the fire box itself.

Although the fire box may have either a hori-

zontal or vertical wall 15, it is preferred however that this wall be sharply inclined as shown in Fig. 1. This permits the coal to be fed down more readily as the coal in the bottom of the fire box is burned. With this inclined wall, the operator of the stove is less likely to punch the wall when pushing down coal. Even if the wall is punched, it will only be with a glancing blow. The sloping top wall 15 also provides for a sharply expanding combustion zone 16. This slows down the velocity of the gases in the top of the stove and results in less fly-ash being carried up through the stack 17. This construction is also more self-cleaning as any fly-ash deposited on the top of the wall 15 will tend to roll down the wall and back into the combustion space in the fire box.

Although the invention has been described as related to a coal stove, it is obvious that it can also be applied to a furnace, a hot water heater, or the like. The by-pass door and the exterior door may be arranged either horizontally, vertically, or inclined.

Having described my invention as relating to various embodiments of the same, it is my intention that the invention be not limited by any of the details of description, but rather be construed broadly within its spirit and scope as set out in the accompanying claims.

I claim:

1. In a coal stove and the like including a fire box and means forming a passageway for gases adjacent the top of the fire box, a door in the fire box adjacent the top thereof normally closing an opening between said passageway and the fire box, a second door adjacent the first door normally closing an opening between said passageway and the exterior of the stove, said first door being hinged mounted on said second door, and single means for opening said first door and said second door.

2. The coal stove of claim 1 wherein means are provided for releasably holding said doors together after the first door has been opened.

JOHN C. MILES.
